UNITED STATES PATENT OFFICE.

HAROLD B. SMITH, OF WORCESTER, MASSACHUSETTS, ASSIGNOR TO WESTINGHOUSE ELECTRIC AND MANUFACTURING COMPANY, A CORPORATION OF PENNSYLVANIA.

COIL FOR ELECTRICAL APPARATUS.

1,082,563.

Specification of Letters Patent.

Patented Dec. 30, 1913.

Application filed January 26, 1910. Serial No. 540,209.

To all whom it may concern:

Be it known that I, HAROLD B. SMITH, a citizen of the United States, and a resident of Worcester, in the county of Worcester 5 and State of Massachusetts, have invented a new and useful Improvement in Coils for Electrical Apparatus, of which the following is a specification.

My invention relates to coils for electrical 10 apparatus and it has for its object to provide a simple coil of spiral form which shall be especially adapted for use in high-voltage transformers and other similar apparatus and a particularly advantageous method of 15 producing the same.

In the construction of very high-voltage 20 transformers, it is often desirable to employ coils which are spiral in form and each of which contains a single layer of turns in order that the coils may readily be insulated 25 from each other and be cooled by contact with the oil or other insulating fluid in which they are immersed. It has heretofore been very difficult to produce a coil of this kind if made of ordinary cotton-covered 30 round wire conductors of small gage. There are, however, many advantages in using conductors of this kind, since they are cheaper than conductors of square or rec- 35 tangular section and present a greater radi- 40 ating surface to the insulating fluid in which they are disposed.

According to my present invention, I provide a coil which comprises a single layer of 45 spirally wound convolutions which are stitched together by a zigzag sewing machine, the stitches alone being depended upon for holding the turns together in the completed coil.

It is evident that coils produced in accordance with my invention may be utilized 50 for various purposes and that they may be formed of conductors of different gages having coverings of cotton, silk or other insulating fabric.

Figure 1 of the accompanying drawings is a perspective view of apparatus suitable 55 for producing the coil which is illustrated in Fig. 2. Figs. 3 and 4 are, respectively, a plan view and an elevation of a guide roll which forms a part of the apparatus of Fig. 1. Fig. 5 is a plan view and Fig. 6 is a partial elevation, on a larger scale, of the mechanism shown in Fig. 1.

Referring to the drawings, the apparatus

here shown comprises a table 1, which may be replaced by any suitable base, a sewing machine 2, which is adapted for zigzag stitching, guide members 3 and 4, a center plate 5 and a guide rod 6 for the center 60 plate.

The guide member 3 is shown in detail in Figs. 3 and 4 and comprises an under plate 7, which substantially corresponds, in thickness, to the diameter of the conducting wire 65 of which the coil is to be wound, an overhanging plate 8, which is secured to the plate 7 and is provided with posts 9 and 10, and a frusto-conical roller 11. The roller is disposed in a recess 12, which is expanded, 70 as shown at 13 in Fig. 3, to avoid interfering with the sewing machine needle and foot when the guide member is assembled on the table 1, as shown in Figs. 1 and 5. The roller 11 is provided with axial extensions 75 14 which project into slots 15 in the posts 9 and 10 in which helical springs 16 are disposed. The springs produce a downward pressure on the extensions 14 of the rolls and their tension may be adjusted by screws 17, 80 which are screw-threaded through caps 18 of the posts. The roller rests upon the coil which is in process of formation and keeps the convolutions flat against the surface of the table just as they are fed to the sewing 85 machine. The post 10 is adjustably mounted on the plate 8 between two stationary blocks 17^a and 18^a, which are screwed to the plate. The adjusting screw 19^a is rotatably supported in the blocks 17^a and 18^a and is screw-threaded through the post 10, so that an 90 adjustment of the post is produced by turning the screw.

The guide member 4 is intended to straighten the conductor as it is formed into the coil and also to guide the convolutions which are already wound. This device comprises a rod or shaft 19, which is supported in bearing blocks 20 and is provided with a frusto-conical projection 21 which extends 95 over the outer edge of the coil near the guide member 3, on the side from which the conducting wire is fed. The bearing blocks 20 are preferably secured to a plate 22 which may be mounted on the table in any suitable position. The shaft may be adjusted longitudinally, in order to vary the position of the frusto-conical projection 21, by means of a screw 23 which is rotatably supported by 100 the bearing blocks directly above the shaft 110

and on which a nut or rider 24 is mounted. The nut is disposed between the bearings 20 and the shaft extends through it, the arrangement of parts being such that the shaft 5 is free to rotate, while any adjustment of the nut produces a corresponding longitudinal adjustment of the shaft and the frustoconical projection.

The guide rod 6 is provided with a longitudinal slot 25 and is pivotally mounted, at 10 its inner end, on the projection 26 of the plate 8. The center plate 5 is provided with a screw-threaded projection 27 which extends upwardly, from its central point, through 15 the slot 25. The nut 28 is screwed upon the projection 27, which extends upwardly from its central point through the slot 25. The nut 28 is screwed upon the projection 27, the arrangement of parts being such that the 20 strip 6 serves as a guide for the center plate 5, which is adjustably mounted on the table 1.

A pulley 29 is pivotally supported upon 25 the under side of the inner end of the rod 26, and a cord or chain 30, which is attached to the projection 27 at its inner end, passes over the pulley 29 and over the guide pulley 31, a weight 32 being attached to its outer end. A second weight 33 is attached to a 30 cord 34 which passes over another pulley 35, located at the opposite side of the table, the inner end of this cord being attached also to the projection 27. The outer end of the rod 6 is screwed to the projection 36 or 35 is otherwise to secure a stationary support.

The method of producing coils by the mechanism above described is as follows: A disk or templet 37, which corresponds, in thickness, to the diameter of the conductor, 40 is concentrically attached to the center plate 5 and rests upon the table 1. The diameter of the templet is made to correspond to the inside diameter of the coil which is to be wound, and the center plate and templet 45 are adjusted until one point in the circumference of the templet is directly under the central position of the needle of the sewing machine. The conductor is then fed, as indicated in Figs. 2 and 5 of the drawings, 50 under the rollers 21 and 11 and is carefully sewed to the disk as shown in Fig. 5. As soon as the first turn of the coil is completed, the second turn is sewed to the first and the ordinary feed mechanism of the sewing machine serves to rotate the disk and the turns 55 already completed, and to automatically wind the spiral. As the sewing process is continued, the center of the coil must necessarily move away from the needle, since the

radius of the coil is constantly increasing 60 and, since the coil is resting on the table, this adjustment is provided by the rod 6, the weights 32 and 33 tending to keep the coil from being forced away too rapidly. When the coil is completed, it is ripped 65 away from the disk 37 and the disk may be used in making other coils.

It has been found, in practice, that relatively fine cotton thread may be employed for sewing cotton-covered conductors of 70 small gage and, if the first turn of the coil is carefully sewed to the templet, there is no danger of breaking the needle of the machine by striking the center of the conductor.

I do not wish to be limited to the mechanism illustrated, since the same result may 75 presumably be secured by means of modified structures.

I claim as my invention:

1. A coil for electrical apparatus comprising a series of convolutions of fiber-covered round wire disposed in a single plane, the successive convolutions of the fiber covering being sewed to each other by zigzag stitches, constituting a series of convolutions. 80

2. A coil for electrical apparatus comprising a flat spiral of fiber-covered small round wire, the successive turns of the fiber covering being sewed to each other by stitches 85 constituting a spiral.

3. A coil comprising a spiral of small cotton-covered wire, the successive turns of the covering being sewed to each other by zigzag stitches constituting a spiral.

4. The method of constructing a coil for 90 electrical apparatus that consists in sewing the first turn to a templet and each succeeding turn to the turn next preceding it.

5. The method of forming coils for 100 electrical apparatus which consists in sewing one turn to a disk or templet and sewing each successive turn to the turn preceding by zigzag stitches.

6. The method of constructing a coil for 105 electrical apparatus which consists in sewing one turn to a disk or templet, gradually rotating the disk, stitching each succeeding turn to the preceding turn and adjusting the center of the coil, according to its increase in diameter, to maintain the stitching point 110 stationary.

In testimony whereof, I have hereunto subscribed my name this sixth day of January, 1910.

HAROLD B. SMITH.

Witnesses:

G. M. CHAMBERLAIN,
ANNA PHELON.

It is hereby certified that in Letters Patent No. 1,082,563, granted December 30, 1913, upon the application of Harold B. Smith, of Worcester, Massachusetts, for an improvement in "Coils for Electrical Apparatus," an error appears in the printed specification requiring correction as follows: Page 2, line 35, for the words "to secure" read *secured to*; and that the said Letters Patent should be read with this correction therein that the same may conform to the record of the case in the Patent Office.

Signed and sealed this 3rd day of February, A. D., 1914.

[SEAL.]

J. T. NEWTON,
Acting Commissioner of Patents.
